UNITED STATES PATENT OFFICE.

CURT L. E. MUELLER, OF JOLIET, ILLINOIS.

MOTOR-FUEL.

1,297,388.

Specification of Letters Patent. Patented Mar. 18, 1919.

No Drawing.

Application filed October 21, 1918. Serial No. 259,056.

To all whom it may concern:

Be it known that I, CURT L. E. MUELLER, a citizen of the United States, and a resident of Joliet, in the county of Will and State of Illinois, have invented certain new and useful Improvements in Motor-Fuel, of which the following is a specification.

My present invention relates to the provision of a fuel suitable for use in internal combustion engines and the objects of my invention are the provision of such a fuel which can be made, at least in part, from substances not heretofore employed in the manufacture of such a fuel, which can be economically made, which will be fully combustible, and which will have, upon combustion, an improved power producing value. The fuel hereinafter described retains sufficient lubricating qualities so as to lubricate the cylinders of an internal combustion engine which materially reduces the amount of lubricant necessary in the running of such an engine and will absolutely prevent the cylinders ever running dry and sticking or freezing, as it is called.

In order to attain the above results, I have had recourse to the so-called "coal tar derivatives" which are the by-products of the destructive distillation of coal in the commercial manufacture of illuminating and heating gas and coke. These derivatives, while very large in number, may be generally and definitely grouped, for the purposes of the present manufacture, into four classes.

In this grouping I have disregarded the ammoniacal fumes which are driven off in the distillation of the coal tar derivatives at the comparatively low temperature of 20 degrees centigrade. The first group of which

I avail myself are what may be styled the "light oils" or crude naphtha, which distil from the coal tar derivatives up to a temperature of 170 degrees centigrade. These oils generally have the characteristic of a specific gravity of less than one; and in the preparation of the light oils for use in my fuel and after they have been extracted by distillation of coal tar derivatives up to a temperature of 170 degrees centigrade, the light oils which I use are prepared by washing them through a solution of sodium nitrite ($NaNO_2$) 60 Baumé. This is done prior to the mixing of the light oils with the distillate derived from crude petroleum.

A second group of coal tar derivatives are called the "dead oils"; and a third group

are the heavy oils or anthracene oils. Both the dead oils and the anthracene oils usually are characterized by specific gravity in excess of one, or that of water, and distil over 60 from the coal tar derivatives at a temperature in excess of 180 degrees centigrade.

I do not employ the dead oils, with the exception of naphthalene, diphenyl, and phenol, in the manufacture of my fuel and these unused dead oils may be separated from the heavy oils, or anthracene oils by treatment with caustic soda or in any other desired manner. After the extraction of the dead oils and the heavy oils from the coal 70 tar derivatives, there remains a fifth class generally but definitely described as "pitch and subsides", but of this class I make no use.

Among the anthracene oils above referred to are anthracene ($C_{14}H_{10}$); chrysene ($C_{18}H_{12}$); pyrene (C_6H_{10}); fluorene ($C_{13}H_{10}$); and retene ($C_{18}H_{18}$). Of the "dead oils" I employ naphthalene ($C_{10}H_8$); diphenyl ($C_{12}H_{10}$); and phenol (C_6H_5OH); and I 80 also employ anthraquinone ($C_{14}H_8O_2$), which is the product of the oxidation of anthracene with chromic acid.

The above, as well as other anthracene oils, can be compounded to form a fuel, in 85 the manner hereinafter described, but I have found that a satisfactory fuel oil may be compounded out of the following materials and in the following manner:

Seventy-five parts of naphthalene are dissolved at, preferably 100 degrees centigrade, in 100 parts of light oils or toluene; fifty parts of diphenyl are dissolved at the same temperature in 100 parts of light oils or toluene; twelve parts of anthracene are dissolved at 100 degrees centigrade in 100 parts of light oils or toluene; five parts of chrysene are dissolved at the same temperature in 100 parts of light oils or toluene; forty parts of pyrene are dissolved at 100 degrees 90 centigrade in 100 parts of light oils or toluene; two and fifty hundredths parts of anthraquinone are dissolved at 100 degrees 95 centigrade in 100 parts of light oils or toluene; thirty parts of fluorene are dissolved 100 at 100 degrees centigrade in 100 parts of light oils or toluene; fifteen parts of retene are dissolved at 100 degrees centigrade in 100 parts of light oils or toluene. 105

After dissolving the naphthalene, pyrene 110 and fluorene in light oils or toluene, these radicals may be treated to produce neutral

picrates and then dissolved in the proportions and in the manner above described for the other radicals. A mixture of the above solutions is then made with the product of 5 distillation of crude petroleum when heated to a temperature up and to 350 degrees centigrade. The comparatively low specific gravities of the solutions above described render it possible to control, within desired 10 limits, the specific gravity of the final composition by taking a greater or less proportion of the aforesaid solutions. The desired flash point also can likewise be controlled in the same manner, as a greater proportion of 15 the solutions will lower the flash point.

I have not set forth herein the proportions for mixing as different specific gravities and different flash points are required in different localities and the requisite specific 20 gravity and flash point can easily be ascertained upon mixture by means of a hydrometer, with a Baumé scale, and in connection with flash tests.

It is believed that the fuel oil, compound- 25 ed as above described, is freely and fully combustible, leaving practically no carbon deposits and producing a satisfactory power, greatly in excess of that of the entire petroleum fuels now generally employed, and will 30 lubricate the engine cylinders.

While I have described a preferred manner of carrying out my invention, I do not desire to be limited to the specific disclosure made herein, for it will be obvious to others 35 skilled in the art that modifications and refinements thereof may be made without materially departing from the teaching and disclosure herein made, it being my intention to claim my invention as fully and completely as the prior state of the art will 40 permit.

What I claim as new is:—

1. A fuel oil comprising a mixture of solutions of anthracene oils in the light oils 45 derived from the fractional distillation of coal tar with the products of the distillation of crude petroleum up and to a temperature of 350 degrees centigrade.

2. A fuel oil comprising a mixture of solutions of anthracene oils in the light oils derived from the fractional distillation of coal tar some of which said anthracene oils have been picrated with the products of the distillation of crude petroleum at a temperature 55 up and to 350 degrees centigrade.

3. A fuel oil comprising a mixture of solutions of naphthalene, diphenyl, anthracene, chrysene, pyrene, anthraquinone, fluorene and retene in the light oils derived from 60 the fractional distillation of coal tar with the products of the distillation of crude petroleum at a temperature up and to 350 degrees centigrade.

4. A fuel oil comprising a mixture of solutions of picrated naphthalene, diphenyl, 65 anthracene, chrysene, picrated pyrene, anthraquinone, picrated fluorene and retene in the light oils derived from the fractional distillation of coal tar with the products of the distillation of crude petroleum at a temperature up and to 350 degrees centigrade.

5. A fuel comprising a mixture of oils derived from coal tars comprising light oils of a specific gravity of less than unity, heavy 75 oils of a specific gravity in excess of unity with the products of the distillation of crude petroleum at a temperature up and to 350 degrees centigrade.

6. A hydrocarbon explosive fuel comprising the products of the distillation of crude 80 petroleum at a temperature up and to 350 degrees centigrade to which are added solutions of heavy oils in the light oils derived from the fractional distillation of coal tar derivatives.

7. A fuel oil comprising the mixture of solutions of the separate radicals of the anthracene group or series in the light oils derived from the fractional distillation of coal tar together with the products of the 90 distillation of crude petroleum at a temperature up and to 350 degrees centigrade in suitable proportions to secure the desired gravity and flashing point.

8. A fuel oil consisting of a mixture of solutions of heavy oils derived from the distillation of coal tar derivatives in light oils derived from the distillation of coal tar derivatives which said light oils have been treated with sodium nitrite, together with 100 the products of the distillation of crude petroleum at temperatures under 350 degrees centigrade.

9. A fuel comprising a mixture of oils derived from coal tars consisting of light oils 105 of a specific gravity of less than unity which have been treated with sodium nitrite, heavy oils of a specific gravity in excess of unity with the products of the distillation of crude petroleum at a temperature up and 110 to 350 degrees centigrade.

10. A hydrocarbon explosive fuel comprising the products of the distillation of crude petroleum at a temperature up and to 350 degrees centigrade to which are added solutions of heavy oils in the light oils derived from the fractional distillation of coal tar derivatives said light oils having been treated in a solution of sodium nitrite.

Signed at Joliet, county of Will and State 120 of Illinois, this 18th day of October, 1918.

CURT L. E. MUELLER.
